UNITED STATES PATENT OFFICE.

CHARLES H. WHEELER, OF EAST PALESTINE, OHIO, ASSIGNOR TO THE NATIONAL TIRE
& RUBBER COMPANY, OF EAST PALESTINE, OHIO.

DESIGN FOR A TIRE.

Application filed December 8, 1923. Serial No. 7,976. Term of patent 14 years.

To all whom it may concern:

Be it known that I, CHARLES H. WHEELER, a citizen of the United States, residing at East Palestine, in the county of Columbiana and State of Ohio, have invented a new, original, and ornamental Design for Tire, of which the following is a specification, reference being had to the accompanying drawing, forming part thereof.

Figure 1 is a plan view of the tire, showing my new design; and

Figure 2 is a transverse sectional view.

I claim:

The ornamental design for a tire as shown.

CHARLES H. WHEELER.
